UNITED STATES PATENT OFFICE.

FREDERICK BAUER, OF WAUSAU, WISCONSIN.

HAIR CLIPPER.

Application filed March 24, 1928. Serial No. 264,557.

This invention relates to hair clippers. One object is to provide a clipper that will automatically so shade the cut that no line of demarcation between long and short cuts will be discernible. A further object is to provide such a clipper wherein the normally automatic mechanism can, at will, be subjected to manual control and be caused to produce a cut to conform to the will or desire of the operator.

With the foregoing and other objects in view the invention consists in the combination and arrangement of parts to be hereinafter fully described, pointed out in the claims and illustrated in the accompanying drawings which form a part of this application for patent, and in which—

Fig. 1 is a perspective view of a hair clipper constructed according to my invention, the handles being omitted.

Fig. 2 is a perspective view of the comb and handles which form the major portion of my attachment.

Fig. 3 is a fragmentary view of the device. Fig. 4 is a perspective view of the clipper without the comb and handles.

Fig. 5 is a fragmentary sectional view of Fig. 2.

Fig. 6 is a vertical sectional view taken on line 6—6 of Fig. 5.

Like reference characters denote corresponding parts throughout the several views.

Electric hair clippers now in general use require a certain amount of skill on the part of the operator for high class work. The cost of the services of a skilled barber is today no small matter to large families and in many communities it is not always convenient, even at the prevailing prices, to obtain such services.

This invention is designed to enable one totally unskilled in the art of high class hair cutting to perform a good job, also to furnish skilled barbers with a device that will enable them to do quicker, more accurate and neater work.

The machine comprises a comb that serves as a support for the ordinary electric clipper, the lower blade of the clipper being lengthened to facilitate its attachment to and operation by the comb. The clipper, proper, is slidably mounted to the comb

upon the inclined upper face thereof in such manner that as the machine is moved over the head upward from the back of the neck the clipper first cuts the hair very short and then gradually longer. Manually operable means are provided, however, whereby the sliding movement of the clipper proper may be arrested so that uniform length cutting may be had when desired.

The reference numeral 1 denotes a pair of hair clippers comprising the movable blade 2 reciprocally mounted to the stationary blade 3 which blade is somewhat wider than the blade 2 to provide for its relative movement, said blade 3 being materially lengthened as shown to permit the application of the attachment. The lengthened blade 3 is formed longitudinally of its under face 4 with the spaced racks 5, 6 along its opposite lateral edges, said racks extending almost, but not quite, from end to end of the blade so that short non-toothed portions 7 are formed at the rack ends.

The comb attachment comprises a casing having the opposed sides 8, 9 connected by the integral end portion 10, base 11 and the bevelled or inclined face 12, the sides 8, 9 so rising above the base 11 and face 12 and being then bent inwardly or toward each other so that diametrically opposed grooves 13, 14 are formed immediately above the face 12. The extended portions of the sides 8, 9 are less extensive than the face 12 or base 11, the said side extensions at one end terminating in the bevelled shoulders 15 that terminate flush with the face 12.

Longitudinally extending parallel slots 16 are provided in the face 12 and base 11 whereby to form teeth 17, the said teeth being curved or rounded somewhat at their free ends, the inner ends of the slots 16 being spaced a substantial distance from the end 10 of the casing. The base 11 of the casing is formed with a transverse perforation 18 to afford clearance for the roller 19 keyed to the shaft 20 that extends transversely of the casing and is journaled in the sides thereof, said roller projecting below the base 11 as shown.

Also keyed to the shaft 20 between the ends of the roller 19 and the sides of the casing are the small gears 21, 22 in mesh with the relatively large gears 23, 24 loosely

upon shaft 25 that is parallel with the shaft 20 and spaced thereabove and connects the sides of the casing, said gears 23, 24 being in mesh with the racks 5, 6 of the stationary blade 3 when the clipper, proper, is operatively received upon the face 12 of the casing, the sides of the blade 3 then being received in the grooves 13, 14.

Adjustably secured in perforations 26 in 10 the end 10 of the casing are the inner ends of the handles 27 that are formed contiguous to the casing with the oppositely disposed hooks 28, said hooks 28 normally being in alignment with the grooves 13, 14 15 so that they may receive and serve as guides for the blade 3 of the clipper as it moves outwardly from the comb. A spring 29 connecting the handles 27 serves yieldingly to retain them in the adjusted spaced 20 relation.

While the hooks 28 are normally in alignment with the grooves 13, 14 the handles 27 diverge outwardly from said hooks so that the blade 3 as it moves out will come in 25 between them and afford clearance for the hand of the operator supporting the handles.

In operation the clipper proper is placed upon the comb casing with the blade 3 in engagement with the recessed sides of the 30 casing, the forward end of the blade 3 being flush with the forward or free ends of the teeth 17 of the comb. The gears 23, 24 now are in mesh with the racks 5, 6. The clipper is now placed so that the free ends of the 35 teeth 17 will be disposed upon the back of the neck where the hair cutting operation is to begin. The current is now turned on causing the clipper to operate. The machine is moved slowly over the head. The 40 roller 19 will travel over the neck and head and slowly, through gears 21, 22, 23, 24 and the racks 5, 6 cause the blade 3, and the clipper proper, to ride outwardly and rearwardly from the face 12 of the comb casing. 45 The hair being cut extends up between the teeth 17 of the comb and is engaged by the blades 2, 3. As the blade 3 moves outwardly over the bevelled face 12 it gradually gets farther and farther away from the hair 50 being cut thus cutting the hair gradually longer and longer as the clipper is guided by the handles 27 over the head.

To cut the hair at any desired length uniformly instead of gradually shorter the 55 operator may at any time press the handles 27 together causing them to arrest the movement of the blade 3 thus locking the gears, racks and roller. The cutting operation will now be performed as before by the 60 blades 2, 3 except that there will be no movement of the blade 3 relative to the casing face 12. When the blade 3 is moved forward until the gears 23, 24 pass beyond the terminal teeth of the rack the relative 65 movement of the blade 3 will then cease and

the clipper will be in initial or starting position again.

What is claimed is:—

1. The combination with a hair clipper, of blades, racks formed upon one blade, a comb comprising a casing formed with a bevelled toothed face to receive said blade, a roller in said casing projecting below the base thereof, gearing operatively connecting said roller and rack whereby to cause movement 70 of said blade relative to said casing, means for retaining said blade and casing in operative relation, handles movably secured to said casing, and guide clamps carried by said handles for operative association with 80 said blade.

2. The combination with a hair clipper, of blades, racks formed upon one blade, a comb comprising a casing formed with a bevelled toothed face to receive said blade, the sides 85 of said casing slidably engaging said blade, a roller in said casing projecting beyond the base thereof, gearing operatively connecting said roller and rack whereby to cause movement of said blade relative to said casing, 90 handles movably secured to said casing, and blade-engaging means carried by said handles.

3. The combination with a hair clipper, of blades, one blade being extended and 95 formed with spaced longitudinally extending racks, a comb comprising a casing formed with a bevelled toothed face to receive said blade, a roller in said casing and extending transversely thereof and in 100 spaced relation to said teeth, gearing operatively connecting said roller and racks whereby to cause movement of said blade relative to said casing, means for retaining said blade and casing in operative relation, 105 handles movably secured to said casing, and hooks integral with said handles contiguous to said casing.

4. The combination with a hair clipper, of blades, one blade being extended and 110 formed with spaced longitudinally extending racks, a comb comprising a casing formed with a bevelled toothed face to receive said blade, the sides of said casing being extended upwardly beyond the top face 115 thereof to receive said blade, a roller in said casing, gearing operatively connecting said roller and rack whereby to cause movement of said blade relative to said casing, hooks 120 contiguous to and normally in alignment with the upwardly extended sides of said casing, and handles carrying said hooks and movably secured to said casing, said handles diverging and extending upwardly as they extend outwardly from said hooks with respect to said casing.

In testimony that I claim the foregoing as my own I have hereby affixed my signature.

FREDERICK BAUER.
